J. PRATT.
WINDOW VENTILATOR.
FILED MAY 9, 1921.

FIG. 1.

FIG. 2.

INVENTOR.

JOHN PRATT.

BY

Seth Stouhaug Jr.
Attest.

UNITED STATES PATENT OFFICE.

JOHN PRATT, OF TORONTO, ONTARIO, CANADA.

WINDOW VENTILATOR.

Application filed May 9, 1921. Serial No. 467,934.

To all whom it may concern:

Be it known that I, JOHN PRATT, a subject of the King of Great Britain, and a resident of the city of Toronto, in the county 5 of York, in the Province of Ontario, Canada, have invented certain new and useful Improvements in Window Ventilators, of which the following is the specification.

My invention relates to improvements in 10 window ventilators and the object of the invention is to devise a simple form of ventilator of this type adaptable for use in winter weather which will supply the room with an adequate amount of fresh air and 15 may be easily and cheaply manufactured and it consists essentially of the arrangement and construction of parts as hereinafter more particularly explained.

Fig. 1 is a front elevation of a window 20 looking from the outside and showing my storm window in place.

Fig. 2 is a vertical section through Fig. 1.

In the drawings like characters of reference indicate corresponding parts in each 25 figure.

1 indicates the window frame which is provided with the usual guide rails 2 and 3 and stop rails 4 and 5 extending across the top of the frame between the guide rails.

30 6 is the upper sash slideable between the guide rails 2 and 3, and 7 is the lower sash slideable between the guide rail 2 and the outer window stop 8. 9 is a storm window which is secured in place by any suitable 35 means. The storm window 9 is slightly less in height than the height of the window frame thereby leaving an opening 10 interposed between the top edge of the storm window and the window frame. 11

40 11 is a cross strip which is secured to the inner face of the storm window flush with the upper edge thereof and adapted to fill the space between the frame of the storm window and the frame of the upper sash 6.

45 It will thus be seen that when the upper sash is lowered so that its upper edge is carried to the upper edge of the cross strip 11, an opening is left for the free passage of air from the outside of the house into

the interior of the room. The cold air passing through this opening enters the room and gradually falls downward displacing the impure air which gradually filters out through the opening or is driven out through other open windows in the house. 12 is a 50 hood which is secured to the window frame so as to extend over the opening 10 formed at the top of the storm window 9. The hood 12 prevents a direct draft of air passing through the opening 10 which would be 55 undesirable in stormy weather and also prevents snow blowing in through such opening. In milder weather the lower sash 7 of the window may be raised and the slotted opening 13 which is usually located at the 60 bottom of all storm windows is opened so as to allow of a freer circulation of air.

From this description it will be seen that I have devised a very simple form of ventilator particularly adaptable for use in 70 winter weather and which will be simple, easy and cheap to make and which will provide an adequate supply of air to ventilate the room efficiently.

If found desirable a strip of wood may 75 be inserted between the parting rails to prevent the frost entering when the window is in the ventilating position.

What I claim as my invention is:

In a window structure, the combination 80 with a window frame and upper and lower sash thereof, of a storm sash suitably secured to the frame and of slightly less height than the height of the frame whereby an opening between the top of the storm sash 85 and the frame is formed, a filling strip secured to the inner face of the storm sash at its upper end and extending from side to side thereof and adapted to fill the intervening space between the storm sash and 90 the upper sash of the window to prevent the inward passage of air between the storm sash and the upper window sash until said upper sash is lowered below the bottom edge of said filling strip without preventing a 95 free inward passage of air into the room.

JOHN PRATT.
